(57) **CLAIM**

The ornamental design for a charger for a smart ring, as shown and described.

DESCRIPTION

FIG. 1 is a top, back, right side perspective view of a charger for smart ring, showing our new design;

FIG. 2 is a bottom, back, left side perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The equal-length broken lines in the drawings depict portions of the charger for smart ring that form no part of the claimed design.

1 Claim, 8 Drawing Sheets
